UNITED STATES PATENT OFFICE.

EDWIN D. CODDINGTON, OF NORTH MILWAUKEE, WISCONSIN.

BACKING FOR CEMENT-COATED WALLS.

1,103,174.

Specification of Letters Patent. Patented July 14, 1914.

Application filed January 18, 1913. Serial No. 742,756.

To all whom it may concern:

Be it known that I, EDWIN D. CODDINGTON, a citizen of the United States, residing at North Milwaukee, in the county of Milwaukee and State of Wisconsin, have invented certain new and useful Improvements in Backings for Cement-Coated Walls, of which the following is a specification, reference being had to the accompanying drawing, forming a part thereof.

This invention relates more particularly to a foundation or backing for cement coated walls which are exposed to the weather, but is applicable to interior work. Its main objects are to provide such a foundation or backing to which the plastic coating will firmly adhere and upon which it will not crack and permit water to reach and destroy or injure the underlying supporting structure; which will be sufficiently rigid, firm and stable and of suitable form and construction to receive the plastic coating without temporary bracing or false work of any kind; which will produce a strong, stiff, durable wall, and which can be completely or mainly prepared in a factory and conveniently stored and shipped in rolls, and can be easily applied to a building, and if desired, additionally reinforced when so applied; and generally to facilitate and improve the construction of walls of this class.

It consists in the construction, arrangement and combination of parts as hereinabove particularly described and pointed out in the claims.

In the accompanying drawing like characters designate the same parts in the several figures.

Figure 1 is an outside elevation of parts of two adjoining reinforced backing sheets as constructed and arranged according to the present invention, to receive a coating of cement; Fig. 2 is an enlarged vertical cross section of the same on the line 2—2, Fig. 1; Fig. 3 is a view on a reduced scale of a web or sheet of the reinforced backing as it is prepared in a factory and partially rolled for storage and transportation; Fig. 4 is an enlarged face view of a portion of a reinforced backing sheet, showing a modification of the metal reinforcement; Fig. 5 is a vertical section thereof on the line 5—5, Fig. 4; Fig. 6 is a face view on a reduced scale, showing a modified arrangement of the metal reinforcing bands; and Fig. 7 is a similar view showing another

modification in the arrangement of the transverse reinforcing bands.

Heretofore the main objection to an outside coating of cement as ordinarily applied, has been in the difficulty in making the coating watertight. When the coating is applied in the usual way with a trowel, some reticulated or slatted foundation therefor, such as wood or metal lathing or wire netting, must be used to form a clench for retaining the plastic coating in place as it is spread thereon. It has been found practically impossible with such a reticulated or slatted foundation, to prevent the cracking of the plastic coating, particularly opposite the openings and joints in the lath or netting, and thus allowing water or moisture to come in contact with and to ultimately destroy or injure the lathing or netting and its supporting framework.

With the reinforced backing constituting the present invention, it has been found that a clench is unnecessary to retain the plastic coating in place, the coating being applied by dashing the cement in a semifluid condition upon the wall in successive thin layers. When so applied upon such a backing, the coating will engage therewith and adhere firmly thereto and will not check or crack when the cement sets or hardens.

Referring to the drawing, and more particularly to Fig. 3, the backing is made of long flexible webs or sheets *a*, of some fibrous material such as building paper or felt, rendered waterproof by being saturated or coated with some suitable material such as coal tar. These webs or sheets may be made of any desired width and reinforced on one or both sides with transverse metal strips or bands, with which they are rolled into small compass for convenience in storage and transportation. As shown in Figs. 1, 2 and 3, these metal reinforcing bands are applied at suitable intervals to opposite sides of the sheets in pairs. One band *d*, of each pair is formed with prongs or clips *c*, struck lengthwise therefrom and forced through the intervening sheet *a* and slits or apertures in the opposite band *b*, thereby securing the bands to each other and to the sheet. On the side of the sheet next to the bands *b*, through which they protrude, the prongs or clips *c* are bent, as shown in Fig. 2, to receive and hold reinforcing wires or rods *e*, which are placed in position when the sheets are spread and applied to a wall.

When the backing is to be reinforced and coated with cement on both sides, as shown in Figs. 1 and 2, the bands *d* are also formed with reversely bent prongs or clips *f*, for receiving and holding reinforcing wires or rods *e* on that side of the backing.

In applying the backing to a building, the sheets *a*, with the transverse reinforcing bands *b* and *d* attached thereto, are unrolled and are usually spread horizontally upon the supporting framework to which they are fastened in any suitable manner by nails or other means, with the lower edge of each upper sheet overlapping the upper edge of the sheet next below it on the outer side thereof, as shown in Figs. 1 and 2. The sections of the backing are bound together and further reinforced on either or both sides, by bending adjacent ends of the bands *b* and *d* around a wire or rod *g*, parallel with the wires or rods *e*, and to add strength to the wall across the horizontal lapped joints of the backing sheets, auxiliary bands *h* or wires may be provided between the main bands *b* and *d*, and bent at their ends around or otherwise fastened to horizontal wires or rods *e* on opposite sides of the joints, as shown in Fig. 1.

The reinforcing wires or rods *e* may be stretched taut and fastened at their ends to joists, studs or framework, and along the horizontal joints between the sections of the backing, the framework on which it is spread may, if desired, be provided with girts *i*, and the backing secured thereto at intervals, to give it greater rigidity and stability. The girts *i* may be made as shown in Fig. 2, of metal channel bars filled with cement or the like, and the backing may be secured thereto by bending adjacent ends of the bands *b* over the proximate upturned edges of the channel bars before they are filled with cement. When the backing has been thus spread and secured upon the supporting framework of the wall, a coating *j* of cement is applied thereto in the manner hereinbefore stated, on each side, the metal channel bar girts *i*, when they are used, being filled as the coating is applied to the inner side of the wall or backing.

When the material of which the waterproof backing sheets *a* is composed is somewhat soft or plastic, it closes around the prongs and other fastenings passing through it, effectively sealing the openings made thereby against the passage of moisture, and the surfaces of the sheets being fibrous and somewhat porous or rough, the cement coating will adhere firmly thereto. When the material of the backing sheets is not sufficiently soft and plastic to close tightly around the prongs and nails or other fastenings which puncture the sheets, the openings made thereby are sealed by coating the prongs, nails or other fastenings

with adhesive cement or paint, which when the prongs, nails or fastenings are forced through the sheets, will effectively fill or cover and close such openings against the passage of water or moisture.

The metal reinforcing strips are so arranged that the nails or other fastenings used to secure the backing to the framework, will pass through them, thereby reinforcing the holes made through the backing sheets and preventing the fastenings from tearing or mutilating the sheets around such holes, so as to permit the passage of water through them to the framework. The bands being nailed at the ends to the framework, or the bands of adjoining sheets being bent at the ends around and connected by a transverse reinforcing wire or rod *g*, as shown in Figs. 1 and 2, are thus held in tension and prevent the bagging of the backing when the cement is applied thereto, and form a continuous reinforcement of the wall in the direction of their length. The prongs or clips *c* and *f*, projecting into and being embedded at intervals in the cement coating, further reinforce the coating and the finished wall vertically or in a direction lengthwise of the bands *b* and *d*.

Referring to Figs. 4 and 5, showing a modification of the backing, the backing sheets *a* may be provided with metal reinforcing bands *b'* on one side only, and these bands may be formed with prongs or clips *c'* specially for fastening them to the backing sheets, and with other prongs *f* and *f'* for receiving and holding longitudinal reinforcing wires or rods *e* on either side or both sides of the backing, such wires or rods being applied to the sheets when they are spread and secured to the framework. The backing thus prepared is coated with cement on either or both sides, as hereinbefore explained. The prongs or clips *c'* are struck from the bands *b'* out of line with the prongs or clips *f* and *f'*, as shown in Fig. 4, in order that the prongs *c'* may be bent flat against the back of the sheets by rolls between which the bands are passed lengthwise, without flattening the hooked prongs or clips *f* and *f'* for holding the wires or rods *e*.

When the backing is to be coated on one side only, the reinforcing rods or wires *e* and the prongs or clips *f* or *f'* therefor may be omitted on the opposite side, and when the prongs *f'* passing through the backing are used, the prongs *c'* may be omitted, the prongs *f'* serving alone to secure the bands *b'* to the backing sheets as well as for holding the reinforcing wires or rods *e* and for engagement with the cement coating.

For use on buildings covered with wood sheeting or having wood supports sufficiently close to one another, the wood structure lengthwise of its grain may be utilized

as a reinforcement for the backing by placing the metal reinforcing bands *b* and *d* or *b'* crosswise of the grain and nailing through them at frequent intervals, and in such cases the wires or rods *e* and the prongs or clips *c*, *f* and *f'* for holding them, may be altogether omitted, the bands being secured to the backing sheets by prongs or clips *c'* which pass through and are bent flatly against the sheets and serve also for engagement with the cement coating.

As shown in Figs. 6 and 7, the transverse reinforcing bands *b'* instead of being applied to the sheets *a* at right angles to their side edges, as shown in the other figures of the drawing, may be arranged obliquely thereto and thus serve to brace and strengthen the backing and the wall of which it forms a part, lengthwise as well as crosswise of the sheets. The bands on each sheet may all be inclined in the same direction or disposed parallel with one another, and in applying the backing to a building arranged at an angle to those of the adjoining sheet or sheets, as shown in Fig. 6; or they may be crossed, as shown in Fig. 7. With either arrangement they may be applied to one side only or to both sides of the sheets, and secured thereto by prongs in any of the ways hereinbefore explained. As shown in Fig. 6, the bands *b'* are nailed at the ends to a girt along the lapped edges of the sheets and thus form a continuous reinforcement across the lap. Longitudinal reinforcing wires or rods *e* may be used with the obliquely disposed bands, which would in that case be formed with hooked prongs or clips, as hereinbefore described, to receive and hold such wires or rods. The construction of the backing with the obliquely disposed bands is such that the sheets can be readily rolled, as shown in Fig. 3.

In the several forms of reinforced backing herein shown and described the prongs struck from the flat metal bands and passing through the sheets to which they are attached form shear resisting fastenings which prevent independent movement or slippage of the bands and sheets, the component parts of the backing thus making a unitary structure or integral which, while comparatively thin and light, is at the same time stiff, strong and stable, even before the application thereto of a cement coating.

Various changes other than those above mentioned, in minor details of construction and in the arrangement of component parts of the reinforced backing may be made, without departure from the principle and scope of the invention, as defined in the appended claims.

I claim:

1. A backing for cement coated walls comprising a flexible sheet of fibrous material reinforced by a number of independent ap-

proximately flat flexible metal bands spaced apart and adapted to engage with and reinforce a cement coating, and metal prongs projecting from the metal strips and passed through the sheet of flexible material to form shear resisting fastenings attaching the bands directly to the sheet material, said bands and sheet forming a substantially integral structure.

2. A backing for cement coated walls comprising a flexible sheet of fibrous material reinforced by approximately flat flexible metal bands, said bands having portions thereof struck-up and passed through the sheet of flexible material and bent laterally to form shear resisting fastenings attaching the bands directly to the sheet material.

3. A backing for cement coated walls comprising a flexible sheet of fibrous material, approximately flat flexible metal reinforcing bands spaced apart and having prongs projecting therefrom and passed through the sheet material to form shear resisting fastenings attaching the metal bands to the sheet, said bands being formed at intervals with clips to receive and hold reinforcing rods transversely to said bands.

4. A backing for cement coated walls comprising a flexible sheet of fibrous material, metal reinforcing bands arranged at intervals in pairs on opposite faces of said sheet, one band of each pair having clips inserted through the intervening sheet and apertures in the opposite band and securing the parts together.

5. A backing for cement coated walls comprising a flexible sheet of fibrous material, metal reinforcing bands secured in pairs to opposite faces of the sheet at intervals by clips formed integrally with and passing from one band of each pair through the intervening sheet and apertures in the opposite band, said clips being bent and adapted to receive and hold reinforcing rods transversely to the bands.

6. A backing for cement coated walls comprising a flexible sheet of fibrous material and metal reinforcing bands arranged in pairs on opposite faces of the sheet and formed with clips or prongs for receiving and holding reinforcing rods on opposite sides of the sheet transversely to the bands, some of said clips or prongs passing through the sheet and securing the bands in place thereon.

7. A backing for cement coated walls comprising lapped sheets of flexible fibrous material having metal reinforcing bands attached thereto at intervals transversely to the horizontal lap between adjoining sheets, and a metal rod parallel with and adjacent to said lap, the adjacent ends of said bands of adjacent sheets being bent around said rod to hold it in place and to tie adjoining parts of the backing together.

8. A backing for cement coated walls comprising lapped flexible sheets having approximately flat flexible metal reinforcing bands attached thereto transversely to the lap, said bands having portions thereof struck-up and passed through the sheets to form shear resisting fastenings attaching the bands directly to the sheets, the bands of adjoining sheets being connected at their ends next to

the lap to form a continuous reinforcement ¹⁰ of the backing across the lap.

In witness whereof I hereto affix my signature in presence of two witnesses.

EDWIN D. CODDINGTON.
